JACQUES EDWIN BRANDENBERGER, OF PARIS, FRANCE, ASSIGNOR TO LA SOCIETE DITE
"LA CELLOPHANE," OF PARIS, FRANCE.

SENSITIVE PHOTOGRAPHIC FILM.

1,221,825.

Specification of Letters Patent. Patented Apr. 10, 1917.

Application filed February 24, 1915. Serial No. 10,274.

To all whom it may concern:

Be it known that I, JACQUES EDWIN BRANDENBERGER, a citizen of Switzerland, and resident of 16 Rue du Louvre, Paris, France, have invented a new and useful Sensitive Photographic Film, which is fully set forth in the following specification.

It is well known that difficulties of all kinds are met with in covering with emulsion photographic or cinematographic films.

On the other hand, it is known that the said films have to be manipulated with the greatest possible care in order to avoid any deterioration of the sensitive layer covering the same.

The film forming the subject of the present invention is arranged in such a manner that its sensitive layer is protected during the emulsioning operations, from atmospheric dust, and said layer remaining subsequently protected from any direct contact, either during the course of manufacture of the film or during its use.

To that end, I employ two sheets, at least one of which is of cellulosic nature, and is transparent and permeable to liquids, while the other may be partially or completely deprived of one of the said properties, or even both; and between these two sheets I introduce the sensitive mass constituted either by salts sensitive to light, generally used in photography, and mixed with a transparent adhesive (for instance collodion, gelatin solutions, rubber solutions, or vegetable extract solutions), or by a transparent and permeable sheet impregnated itself with sensitive solutions; in the latter case, the connection of the three sheets is still effected by means of a transparent adhesive of the same nature as above.

The composite film therefore comprises: either (1) two films of pure cellulose (obtained by starting from viscose or cupro-ammoniacal solutions of cellulose) between which is placed either the sensitive emulsion, for instance of gelatino-bromid, or a third film impregnated with solutions of salts sensitive to light, or (2) a pure cellulose film and a sheet, whether transparent or not, permeable or not, separated from each other in the same manner.

The first of these two films is chiefly intended for use in cinematographs.

The accompanying drawing represents, on a greatly-enlarged scale, two cross-sectional

views of the improved film, Figure 1 showing the form of the composite film when the sensitive emulsion is used, and Fig. 2 showing the form which said film takes when the intermediate cellulosic film is utilized.

60

In both figures, 3 and 4 indicate the two outer films, one of which, as stated above, is constructed of pure cellulose. The other of these two films may likewise be constructed of pure cellulose, or it may, if preferred, be constructed of glazed paper, cardboard, metal-coated cellulose and the like, and may, or may not, be transparent and permeable to the liquids used in photography. In either case, however, both films are separate and distinct entities, and they are in a finished state prior to being united by the sensitized material, in which respect they differ radially from successive layers or coatings which are applied one upon another, or upon opposite faces of a blade or body.

65

In Fig. 1, 5 indicates the sensitive emulsion, which is supplied in liquid form between the inner faces of the two films 3 and 4. Any desired apparatus may be utilized to effect the adhesion of the two films, but it is preferable to carry out this step by passing the films from opposite directions to and between a pair of suitable pressure rolls, and to discharge the emulsion upon the inner surfaces of said films at the bite of the rolls, so that the latter will feed the films between them and, at the same time, will join them together face to face. On emerging from the rolls, the composite film may be dried, and thereafter wound up in any desired manner.

70

In Fig. 2, 6 indicates the intermediate film, which is preferably in the form of a cellulose film impregnated with a sensitizing solution. The union of the three films may be effected in substantially the same way as in the first form, excepting that the opposite surfaces of the intermediate film and the inner surfaces of the two outer films are coated with the adhesive which is delivered, as before, to or at the bite of the pressure rolls.

75

Claims:

1. A composite photographic film, comprising two separately-constructed, outer films, and an intermediate stratum or layer containing sensitive material disposed between the inner surfaces of said films, said

80

110

outer films and said intermediate stratum being united face to face throughout their entire extent; at least one of said outer films being constructed of cellulose, and being transparent and permeable to the liquids employed in photography.

2. A composite photographic film, comprising three separately-constructed, coördinate films united face to face throughout their entire extent; at least one of the two outer films being constructed of cellulose, and being transparent and permeable to the liquids employed in photography, and intermediate the film being constituted by 15 a continuous transparent sensitized sheet.

3. A composite photographic film, comprising three separately-constructed, coördinate films united face to face throughout their entire extent; at least one of the two outer films being constructed of cellulose, 20 and being transparent and permeable to the liquids employed in photography, and the intermediate film being constituted by a continuous transparent strip of cellulosic material impregnated with a sensitizing liquid 25 and a transparent adhesive.

In testimony whereof I have signed this specification.

JACQUES EDWIN BRANDENBERGER.
